UNITED STATES PATENT OFFICE.

OSWALD DUDA, OF SOUTH HOUSTON, TEXAS.

CENTRIFUGAL PUMP.

1,287,920.

Specification of Letters Patent. Patented Dec. 17, 1918.

Application filed February 1, 1917. Serial No. 146,020.

To all whom it may concern:

Be it known that I, OSWALD DUDA, a citizen of the United States, residing at South Houston, in the county of Harris and State of Texas, have invented certain new and useful Improvements in Centrifugal Pumps, of which the following is a specification.

This invention relates to new and useful improvements in a centrifugal pump. The object of the invention is to provide a pump of the character described, provided with a deflector, having spiraled vanes, fixed relative to the inlet which are provided to impart a whirling motion to the inflowing fluid before it comes within the range of the runner.

As is well known the fluid is drawn into the pump by suction, created by the spiraled vanes of the rotating runner, the reaction causing an end thrust on the runner shaft which is sustained by a thrust-bearing, with which pumps of the ordinary construction are equipped. The rotation of the shaft, and the end thrust sustained thereby often cause this bearing to become very hot and to quickly burn out; the shaft of the ordinary centrifugal pump is also subjected to considerable torsional strain in imparting a rotary motion to the fluid in the pump and it is the object of this invention to relieve said shaft of the end thrust and torsional strain by delivering, to the runner, the fluid already in rotary motion.

With the above and other objects in view the invention has particular relation to certain novel features of construction, operation, and arrangement of parts, an example of which is given in this specification and illustrated in the accompanying drawings, wherein:

Figure 1 is a horizontal sectional view of the pump, and

Fig. 2 is a vertical sectional view thereof.

Referring now more particularly to the drawings, wherein like numerals of reference designate similar parts in each of the figures, the numeral 1 refers to the pump shell or casing, which, in general contour, is circular, and has the removable end plate 2 having the central fluid inlet 3. Opposite the inlet is a deflector formed of an inverted conical shaped disk 4 and the spiraled vanes,

5, said disk being fixed relative to the end plate by means of said vanes. The vanes are spaced apart and are integral with said 55 plate and disk. This deflector imparts rotary movement to the fluid entering through the inlet 3.

The runner is formed of the disk 6, the ring 7 and the spiraled vanes 8, arranged 60 between, and integral with, them. The runner rotates in countersunk bearings in the end plate 2 and the opposite part of the pump casing, respectively thus fitting closely within the casing and surrounding 65 the deflector.

The runner is fixed upon a shaft 9 which rotates in a suitable stuffing box 10, carried by the casing. Rotation is imparted to the runner, in the direction indicated by the arrow in Fig. 1, by this shaft, and the fluid is drawn into the pump through the inlet 3 and discharged through the outlet 11. The stationary deflector imparts a spiraled or whirling movement to the fluid and delivers 75 it to the runner vanes, in motion, thus relieving the runner and runner shaft of the strain incident to overcoming the inertia of fluid inflowing in a direct current.

What I claim is:

A device of the character described including a casing, a removable end plate having a fluid inlet, fixed to the casing, a deflector opposite the inlet formed of an inverted conical shaped disk, spiraled vanes 85 integral with and located between the end plate and the deflector, said vanes fixing the deflector relative to the end plate, and being spaced apart and provided to impart a rotary motion to fluid passing in the inlet, 90 and a runner surrounding the deflector and including a disk, a ring, spiraled vanes, spaced apart and arranged between and integral with the disk and ring, the end plate and the opposing portion of the pump casing being provided with counter-sunk bearings 95 in which the runner rotates.

In testimony whereof I have signed my name to this specification in the presence of two subscribing witnesses.

OSWALD DUDA.

Witnesses:

E. V. HARDWAY,

A. C. SPRINGFIELD.
